DESIGN FOR A GAME DEVICE

Myron S. Wright, North Hollywood, Calif.

Application August 22, 1940, Serial No. 94,553

Term of patent 7 years

To all whom it may concern:

Be it known that I, Myron S. Wright, a citizen of the United States, residing at North Hollywood, in the county of Los Angeles and State of California, have invented a new, original, and ornamental Design for a Game Device, of which the following is a specification, reference being had to the accompanying drawing, forming a part thereof.

Fig. 2 is a side elevational view thereof.

Fig. 3 is a fragmentary sectional view taken on line 3—3, Fig. 1.

I claim:

The ornamental design for a game device, as shown.

MYRON S. WRIGHT.
